CLAIM

The ornamental design for a gate hinge as shown and described.

DESCRIPTION

FIG. 1 is a front perspective view of the gate hinge.

FIG. 2 is a back perspective view of the gate hinge of FIG. 1.

FIG. 3 is the front view of the gate hinge of FIG. 1.

FIG. 4 is a back view of the gate hinge of FIG. 1.

FIG. 5 is a top view of the gate hinge of FIG. 1.

FIG. 6 is bottom view of the gate hinge of FIG. 1.

FIG. 7 is a side view of the gate hinge of FIG. 1.

FIG. 8 is the other side view of the gate hinge of FIG. 1.

FIG. 9 is a front elevated view thereof, reduced in scale and attached to an unclaimed gate assembly.

FIG. 10 is a front elevated view thereof, reduced in scale and showing the gate hinge in an alternative configuration on the unclaimed gate assembly; and,

FIG. 11 is an enlarge detailed view of area 11 circumscribed in FIG. 10.

The broken lines in the drawings depict portions of the gate hinge that form no part of the claimed design. The additional broken lines in FIGS. 9-11 illustrating a gate apparatus depict environmental subject matter that form no part of the claimed design. All other broken lines in FIGS. 10-11 denote the boundary of the detail area-and form no part of the claimed design.
